(57) **CLAIM**

The ornamental design for a bottle, as shown and described.

DESCRIPTION

FIG. 1 is a perspective view of a bottle according to our new design;

FIG. 2 is a front elevation view thereof, the rear, right side, and left side elevational views being identical thereof;

FIG. 3 is a top plan view thereof;

FIG. 4 is a bottom plan view thereof; and,

FIG. 5 is a cross-section view taken along line 5—5 as shown in FIG. 2.

The broken lines shown in the drawings are for environmental purposes only and form no part of the claimed design.
